UNITED STATES PATENT OFFICE.

HIRAM S. CHAPMAN, OF PENN, MICHIGAN, ASSIGNOR OF ONE-HALF TO
KARL E. RUDD, OF SHELDON, DAKOTA TERRITORY.

SHEAF-CARRIER FOR SELF-BINDING HARVESTERS.

SPECIFICATION forming part of Letters Patent No. 314,364, dated March 24, 1885.

Application filed December 28, 1883. (No model.)

To all whom it may concern:

Be it known that I, HIRAM S. CHAPMAN, of the township of Penn, in the county of Cass and State of Michigan, have invented certain new and useful Improvements in Sheaf-Carriers for Self-Binding Harvesters; and I do hereby declare the following to be a full, clear, and exact description of the invention, such as will enable others skilled in the art to which it appertains to make and use the same.

My invention relates to an improvement in sheaf-carriers for self-binding harvesters, the object of the same being to provide a sheaf-carrier which can be readily adjusted and removed, will allow the sheaves to slide from it without danger of entanglement, and which will sustain the required number of sheaves without sagging, a further object being to provide a mechanism whereby the carrier can be promptly operated by the driver's foot.

With these ends in view, my invention consists in certain features of construction and combinations of parts, as will be fully described, and pointed out in the claims.

In the accompanying drawings, Figure 1 is a view of the carrier-frame and operating mechanism attached to a harvester. Fig. 2 is a detached view of the carrier-supporting frame. Fig. 3 is a detached view of the sheaf-pan. Fig. 4 is a detached view of the stirrup and strap. Fig. 5 is a detached view of a pair of braces.

A represents a laterally-extending supporting-bar, of suitable form and strength to afford a firm support for the forward end of the frame. This bar is provided with the round tapering end *a*, which is secured in the collars *B* by means of the pin *b*, and allowed a rotary motion therein. The collars *B* are secured firmly to the frame of the binder. Three pairs of braces, *CC'C'*, are attached at one end to the supporting-bar *A*, in position as shown in the drawings. Each pair consists of an iron and wooden part firmly fastened together at one end, and spread in such a manner as to embrace opposite sides of the supporting-bar *A* at the other end, and are secured to this bar by a bolt. The parts of each pair *C*, *C'*, and *C''* are arranged in such a manner that the tensile strength of the iron and compressive strength of the wood are brought into action by

the weight upon the carrier. The pairs *C* and *C'* are each secured to the bar *A* by a single bolt, *c*. To complete the supporting frame of the carrier, the ends of these pairs of braces are connected by the bar or rod *D*. The rear end of the carrier is supported and operated by means of straps, cords, or chains passing around the rolling rod *E*. One end of this rod *E* is secured to the frame of the binder, preferably at the rear of and below the driver's seat, by the universal joint *F*. One of the straps, *e*, has one end fastened to the rolling rod *E*, near the end toward the carrier, and after passing a sufficient number of times around this rod is fastened to the end of the projecting arm *f* of the carrier by a snap-hook. This arm *f* is of a sufficient length and extends in such a direction as to place the strap *e* where it will not hinder the free discharge of the sheaves from the carrier. A second strap, *e'*, has one end fastened to the rod *E* a short distance from the position of the strap *e* toward the center of the rod, and after passing around the rod a suitable number of times is secured to the frame of the binder above the said rod. A third strap, *e''*, has one end fastened to the rod *E* at a short distance from the joint *F*, and after passing around the rod *E* a suitable number of times is secured to the end of the rearwardly-extending arm *G* on the "stirrup" or treadle *H*. The stirrup *H* consists of a downwardly and forwardly extending curved portion, *h*, and a downwardly and rearwardly extending part *h'*, the part *h'* being provided at its lower end with the laterally-extending foot-rest *h''*. The two parts *h* and *h'* are formed integral or firmly joined at their upper portions, and are provided with a perforation by means of which they are pivoted in a depending position on the rod *K*. The rearwardly-extending arm *G*, to which the strap *e''* is attached, is pivoted at one end to the curved portion *h* of the stirrup *H*. The straps *e e' e''* are wound about the rod *E* in such directions that when power is applied to the strap *e''* a single revolution of the rod *E* will raise the rear end of the carrier-frame a distance equal to two circumferences of the rod *E* at the end where the straps *e* and *e'* surround it, and as the said rod *E* can be made much larger at this end than near the joint *F*,

where the strap e^2 encircles it, the arm G will be required to move but a short distance to elevate the carrier-frame a great distance. Suppose the rear of the carrier-frame to be depressed and the several arms of the stirrup or treadle H to occupy the position represented by the dotted lines in Fig. 4. The driver presses his heel on the laterally-extending foot-rest h³, and thereby throws the stirrup into the position noted by full lines in Fig. 4, or until the pivoted end of the arm G is thrown past the center and thereby locked in position. This will draw on the strap e^2 and raise the carrier in the manner explained above. To drop the carrier, the driver presses his toe on the end of the arm h, and thereby unlocks the arm G, and allows the stirrups to swing into the position noted by the dotted lines in Fig. 4, which loosens the straps e^2 , and allows the straps e and e' to unwind and the rear end of the carrier to fall.

The carrier, receiver, or pan M is provided with three outwardly-flaring sides to hold the sheaves from shaking off, the rear end being left open to allow the sheaves to readily slide off when the rear end is depressed. This pan M is removably secured to the carrier-frame by bolts or other suitable means.

I am aware that a rearwardly-tilting carrier is not new; but by the construction above recited I am enabled to remove the sheaf-carrier with greater facility, since I have only to release the snap-hook from the arm f, and remove the pin from the end of the supporting bar A. I have also a smooth surface to receive the sheaves from the ejector-arms, and the clogging, which has been a disadvantage heretofore, is effectually avoided.

The manner of bracing the carrier-frame, combining lightness with strength, and the mechanism by which the carrier is operated by the foot, are also advantages of great importance over the sheaf-carriers heretofore made.

It is evident that slight changes may be made in the form and arrangement of the several parts without departing from the spirit

and scope of my invention. I do not therefore limit myself to the exact construction herein set forth; but,

50

Having fully described my invention, what I claim as new, and desire to secure by Letters Patent, is—

1. In a sheaf-carrier, the combination, with a rocking shaft and braces rigidly secured thereto, forming a supporting-frame, of a receiver or sheaf-receptacle rigidly secured on said frame and devices for raising and lowering one end of said frame, substantially as set forth.

60

2. In a sheaf-carrier, the combination, with a rearwardly-tilting frame, of a rolling rod attached to the harvester-frame and operated by a treadle, and flexible straps connecting the rod with the tilting frame and the treadle with the rod, substantially as set forth.

3. In a sheaf-carrier, the combination, with a tilting frame, of a rod loosely mounted at one end in the frame of the harvester, and connected at its other end by flexible devices to the tilting frame, and a treadle for operating the rod, and connected thereto by flexible devices, substantially as set forth.

70

4. In a sheaf-carrier, the combination, with a rocking shaft and a receiver or sheaf-receptacle rigidly secured thereto, of the treadle having the curved portion h, the curved arm secured to said curved portion of the treadle, and devices connecting the arm and receiver, substantially as set forth.

80

5. In a sheaf-carrier, the combination, with a rocking shaft, of braces secured thereto in pairs, each pair constructed of two different materials, the whole forming a support for a receiver, and devices for holding the movable end of the supporting-frame in the required vertical adjustment, substantially as set forth.

85

In testimony whereof I have signed this specification in the presence of two subscribing witnesses.

HIRAM S. CHAPMAN.
